UNITED STATES PATENT OFFICE.

STANLEY A. MARTINEK, OF AMARILLO, TEXAS.

PRIMING-CUP FOR INTERNAL-COMBUSTION MOTORS.

1,329,464.

Specification of Letters Patent.

Patented Feb. 3, 1920.

Application filed January 31, 1919. Serial No. 274,278.

To all whom it may concern:

Be it known that I, STANLEY A. MARTINEK, a citizen of the United States, residing at Amarillo, in the county of Potter and State of Texas, have invented certain new and useful Improvements in Priming-Cups for Internal-Combustion Motors, of which the following is a specification.

This invention relates to a priming cup for internal combustion engines or motors and an object of the invention is to provide a priming cup which is screwed into the head of the motor, which is simple in construction, durable, and easily operated to permit the volatile fluid to flow therethrough into the cylinder to the engine.

More specifically, the invention comprehends the provision of a primer or priming cup as specified, which includes a casing having a shank thereon, which is threaded into the cylinder head and in which casing is mounted a longitudinally movable spring controlled valve member having a head upon its upper end provided with an annular groove adapted to engage over a portion of the casing to hold the valve in an open position and which head springs or moves into the opening in the casing through which a head projects, to reseat the valve cone and shut off the passage of fluid to the priming cup.

Other objects of the invention will appear in the following detailed description taken in connection with the accompanying drawing, forming a part of this specification and in which drawing:

Figure 1 is a side elevation of the improved priming cup showing the same applied to a fragment of an internal combustion engine.

Fig. 2 is a longitudinal section through the priming cup showing the valve closed, and

Fig. 3 is a longitudinal section through the priming cup showing the valve open.

Referring more particularly to the drawing, A indicates a fragment of an ordinary internal combustion engine or motor, the head B of which is provided with a threaded bore C. This threaded bore C receives therein the threaded end 1 of the shank 2 of the casing or main body 3 of the priming cup to connect the priming cup to the engine. The head B is provided with a polygonal face 4 to permit it to be gripped by a wrench for properly connecting it to the cylinder

head B, and it is also provided with a relatively large recess 5 therein which opens out through a constricted opening 6 in the upper end of the body. The shank 2 is provided with an axial bore 7, the upper end of which is enlarged as shown at 8 to receive therein the lower end of the spiral spring 9 and also to form a shoulder against which the lower end of the said spring abuts. 60 The spring 9 is coiled about the valve stem 10 and its upper end abuts against the inner end of the head 11 which is detachably mounted upon the upper end of the valve stem 10. This head 11 is provided with a 65 substantially conical cup or recess 12 opening out at its upper end which communicates with a transverse bore 13 in the head through an axial bore 14. The transverse bore 13 is formed in the head 11 so that it will be at 70 all times positioned within the recess 5.

The head 11 is provided with an annular recess 15 which is normally positioned out of the casing or body 3.

When it is desired to prime the internal 80 combustion engine with which the improved priming cup is used, the spouts of an ordinary oil can as indicated at D in Fig. 3 of the drawings is inserted into the recess 12 and the head 11 is forced inwardly against 85 the tension of the spring 9 for unseating the valve cone 16 which is carried upon the lower end of the stem 10 and normally rests in the valve seat 17 formed in the lower end of the shank 2. After the head 11 and stem 90 10 has been forced inwardly to unseat the valve cone 16, they are forced laterally, a short distance so that the flange which surrounds the opening 6 will be engaged in the recess 15 and the expanding action of the 95 spring 9 will force the lower wall of the annular recess 15 into firm engagement with the flange of the body 3 which surrounds the opening 6, maintaining the head 11 and the valve stem 10 in their angular positions, al-

lowing gasoline or other volatile fuel, which may be forced into the recess 12 from the can D to flow through the ducts 14 and 13 into the recess 5 and through the axial bore 7 through the shank 2 into the engine. A slight 100 lateral pressure on the head 7 to move it sufficiently to disengage the flange of the body 3 from the annular channel 15 will allow the spring 9 to seat the head in the opening 6 and also seat the valve cone 16 cutting off the flow of fluid through the priming cup. 110

Changes in details may be made without departing from the spirit of this invention, but;

I claim:

- 5 1. In a priming cup for internal combustion motors, a body provided with an axial bore and with a recess opening out through a constricted opening in the upper end of the body, a valve stem extending axially through said body, a head carried by said stem and extending through said restricted opening, a valve cone carried by the stem and normally preventing the passage of fluid through said body, and means upon said head for engagement with said body upon depression and slight lateral movement of the head to hold the valve cone unseated.
- 10 2. In a priming cup for internal combustion motors, a body provided with an axial bore and with a recess opening out through a constricted opening in the upper end of the body, a valve stem extending through said bore, a head carried by the upper end of said stem and extending through said constricted opening, a valve cone carried by the stem and normally preventing the passage of fluid through said body, said head provided with a fluid receiving recess and with a transverse duct communicating with the recess in said body, and means upon said head for engagement with said body upon depression and slight lateral movement of the head to hold the valve cone unseated.
- 15 3. In a priming cup for internal combustion motors, a body provided with an axial bore and with a recess opening out through a constricted opening in the upper end of the body, a valve stem in said bore, a head carried by the upper end of said stem and extending through said constricted opening, a valve cone carried by the stem and normally preventing the passage of fluid through said body, said head provided with an annular recess adapted for engagement with a portion of the body surrounding said constricted opening upon depression and slight lateral movement of the head to hold the valve cone unseated.
- 20 4. In a priming cup for internal combustion motors, a body provided with an axial bore and with a recess opening out through a constricted opening in the upper end of the body, a valve stem in said bore, a head carried by the upper end of said stem and extending through said constricted opening, a valve cone carried by the stem and normally preventing the passage of fluid through said body, said head provided with an annular recess adapted for engagement with a portion of the body surrounding said constricted opening upon depression and slight lateral movement of the head to hold the valve cone unseated, said head provided with a fluid-directing recess and with a transverse bore having communication with

said recess and with said body carried recess for conveying fluid from the head carried recess into the body for passage therethrough when said cone valve is unseated.

5. In a priming cup for internal combustion motors, a body provided with an axial bore and with a recess opening out through a constricted opening in the upper end of the body, a valve stem in said bore, a head carried by the upper end of said stem and extending through said constricted opening, a valve cone carried by the stem and normally preventing the passage of fluid through said body, said head provided with an annular recess adapted for engagement with a portion of the body surrounding said constricted opening upon depression and slight lateral movement of the head to hold the valve cone unseated, said head provided with a fluid-directing recess and with a transverse bore having communication with said recess and with said body carried recess for conveying fluid from the head carried recess into the body for passage therethrough when said cone valve is unseated, a spring coiled about said valve stem and engaging said head for normally holding the valve cone seated to cut off the supply of fluid through the cup.

6. In a priming cup for internal combustion engines, a body provided with an axial bore opening out through a valve seat in its lower end, a valve stem extending through its body, a valve cone on the lower end of said stem for seating in said valve seat to close said bore, means normally maintaining said cone in said seat, said stem adapted to be depressed and moved laterally to unseat said valve cone.

7. In a priming cup for internal combustion engines, a body provided with an axial bore opening out through a valve seat in its lower end, a valve stem extending through said body, a valve cone on the lower end of said stem for seating in the valve seat to close said bore, means normally maintaining said cone in said seat, said stem adapted to be depressed and moved laterally to unseat said valve cone, a head upon said stem adapted to engage said body upon depression and lateral movement of the stem to hold the valve cone unseated.

8. In a priming cup for internal combustion engines, a body provided with an axial bore opening out through a constricted opening in the upper end of the body, a valve stem extending axially through said body and extending through said restricted opening, a valve cone carried by the stem and normally preventing the passage of fluid through said body and means upon said stem for engagement with said body upon depression and slight lateral movement of the stem to hold the valve cone unseated.

9. In a priming cup for internal combus-

- tion motors, a body provided with an axial bore adapted to permit the introduction of material into an engine cylinder, a valve stem extending through said bore, means on 5 said stem normally preventing the passage of fluid through the body, said valve stem adapted to be depressed and moved laterally a slight distance to permit the passage of fluid through said bore.
- 10 10. In a priming cup for internal combustion motors, a body provided with an axial bore, adapted to permit the introduction of

material into an engine cylinder, a valve stem extending through said bore, means on 15 said stem normally preventing the passage of fluid through the body, said valve stem adjusted to be depressed and moved laterally a slight distance to permit the passage of fluid through said bore, and means upon 20 said stem for engagement with said body to hold said stem in a depressed lateral position.

STANLEY A. MARTINEK.
